UNITED STATES PATENT OFFICE.

JAMES CUTHBERT PETTIT, OF CREWE, VIRGINIA.

SYSTEM FOR LOCATING ERRORS IN CALCULATIONS.

1,000,291.

Specification of Letters Patent. Patented Aug. 8, 1911.

Application filed September 3, 1910. Serial No. 580,366.

To all whom it may concern:

Be it known that I, JAMES CUTHBERT PETTIT, a citizen of the United States, residing at Crewe, in the county of Nottoway and 5 State of Virginia, have invented a new and useful System for Locating Errors in Calculations; and I do hereby declare the following to be a full, clear, and exact description of the invention, such as will enable 10 others skilled in the art to which it appertains to make and use the same.

This invention belongs to the art of mathematical calculating, and it particularly relates to a new and useful system for 15 locating errors in calculations, and the primary object of the invention is to provide such a system in which there is involved various novel characteristics.

It is a well known fact, among clerks in 20 their various callings, for instance book-keeping and other clerical work, drafting, and engineering, that the majority of errors in calculating result from the transposition of figures (which are transposable) and it is 25 a further fact that heretofore these errors have been exceedingly difficult to trace or locate more than any other class of errors. Moreover, it is well known and a regular occurrence, that an error of 9 or a multiple 30 of 9 results from a transposition.

The fundamental object of this system is to facilitate the finding and the location of the error of transposition, in order that it may be immediately corrected. It is evident, however, that a system of this character saves time, labor and considerable thought. To locate or find an error of 9 (which may result from the transposition of 1 to 10 or vice versa, or from 12 to 21 or 35 40 vice versa, and on through a series of numbers up to 89 and 98, in which there is a difference of 9), you will find the transposed number in column one, at the top of which the numeral 9 is indicated. To find an error of a multiple of 9, say for instance 18 or 45 50 55 60 65 70 75 80 85 90 95 100 105 27, you will find the transposed number in column two or three. The numbers consecutively arranged in any one of the columns shown in the drawings have a difference of 9 or a multiple thereof, and by these columns of numbers one may ascertain the transposed number.

In the drawings there is only disclosed

one arrangement of numbers, but in practical fields this arrangement may be varied, 55 and provided the varied arrangement is comprehended by the claim, the applicant is entitled to it.

Other features and combination of parts will hereinafter appear throughout the 60 specification, and shown in the drawings and claims. In the drawings, however, there is disclosed a chart, upon which columns of various transposable numbers are arranged, with full directions arranged 65 above the columns, in order that one may ascertain the use of this system.

Referring to the drawings 1 denotes a chart which may be made of any suitable card-board or other material, upon which is 70 drawn a square outlined space 2. This space is divided in order to provide 81 square outlined spaces 3. By providing these spaces 3 vertical and horizontal columns are formed. The vertical columns are 75 designated by the numerals 4, 5, 6, 7, 8, 9, 10, 11 and 12, it being understood, however, that column 4 is the first column, while the others are the second, third and fourth columns, etc., up to the ninth which is designated by 12. Column 4 contains various numbers, the differences between them being 80 85 90 95 100 105 9. Column 5 has a plurality of numbers, which may be transposed to obtain a difference of a multiple of 9, for example 18. The other columns from 6 to 12 inclusive have arranged therein various numbers, the differences between which are also a multiple of 9, for example, 27, 36, 45, 54, 63, 72 and 81. These numbers 27, 36, 45, 54, 63, 72, and 90 95 100 105 113 are designated by the character 13. Below each column the transpositions of the differences between the numbers in the columns below the line 14 are indicated, and are denoted by the character 15. These numbers 15 when transposed read 90, 81, 72, 63, 54, 45, 36, 27, and 18. The blank spaces 16 may be used for other transposable numbers, say for example, numbers above 100. The transposition of numbers above 100, occur generally in the last two figures, such as the transposition of 101 to 110 or 112 to 121, the differences between which are 9; or such as the transposition of 102 to 120, or 103 to 130, or 113 to 131. It will be noted, that by 105 the transposition of these last mentioned

numbers, the result would be a multiple of 9, such as 18 and 27. It is evident, however, that the present invention is not to be confined to the special arrangement, as shown in the drawings; it is to be granted that the transposable numbers may be increased in denomination, and arranged upon the chart in any desirable manner. Furthermore, the chart may be varied in design and contour; moreover, the directions 17 and other data 18, at the top and bottom of the chart, may be added to or condensed, in order to facilitate the use of this system.

As a commercial proposition this system affords an excellent medium, as an advertiser, and in practical fields it is found to be indispensable. It is to be remembered, that the owners of the rights in this invention may, as an inducement, advertise banks or other business houses upon the backs or the margin of the charts. That is to say, when a bank pays for the use of this system, it will receive charts with the advertisements of other business houses upon them, and their advertisements are placed upon other distributed charts, as an inducement. By this method, an endless chain of advertising is produced.

A clerk in totaling a column of figures consisting of two rows, finds that the result does not agree with the cash, books or other numerical records. The difference or error, is caused by the transposition of a number, the difference between which results in 9 or a multiple thereof. If the error be 18, the clerk necessarily looks in column 5, over which the numeral 18 is disposed, and he will find the number (which has been transposed) he is adding in with others in said column 5, by comparing this column 5 of transposable numbers with the numbers he is adding. In this way one may locate the number which has been transposed.

In a department store or business house when comparing the sum total of the cash with the sum total of the amounts of a plurality of sales itemized in a ledger, it is desired to locate or trace an error, say for instance an error of 18, which is the result of the transposition of a number, it is accomplished in the following manner:

Immediately below two columns of figures are disclosed as follows:

	Amounts of checks.	Amount of sales in ledger.
55	\$34.00	\$34.00
	72.00	72.00
	64.00	64.00
	42.00	24.00
60	45.00	45.00
	57.00	57.00
	Total.....	Total.....
	\$314.00	\$296.00

It will be observed that there is a difference of \$18.00 between the sum totals of the

checks and the amount of sales in the ledger, as shown by the subtraction of the sum total of the amount of sales from the sum total of the checks as follows:

Sum total of the amount of checks	\$314.00	70
Sum total of the amount of sales	296.00	
The difference between the two sum totals	\$18.00	75

As a general rule this difference is caused by the transposition of a number, for example, two clerks, one calling out the amounts of the checks to the other transposed one of the amounts of the checks. The clerk who may be calling the amounts out may dictate one number when he should have said another, or the other clerk in taking the dictation may write one number when he should have written a different one, for instance, as will be observed one number has been written \$42 when it should have been \$24, as shown in the column of the amount of checks. To locate the transposition of the amount of this particular check, the difference between the sum totals of the checks and amount of sales is learned by the above subtraction, which is \$18, and by looking in the column which is designated by the numeral 5 in the drawings, with 18 at the top thereof you will find the numeral 24, which has been transposed to 42 by the clerk when writing the amounts of the checks, as shown above. This system of locating transposed numbers has served an excellent purpose in various business houses, in lessening the work of the cashiers and bookkeepers and bankers. Without this system it is necessary to run over columns of figures (in which there may be fifty to a hundred or more numbers) several times before locating the number which has been transposed.

The invention having been set forth, what is claimed as new and useful is:

1. A chart having transposable numbers arranged in columns, with the difference between them indicated at the top of each column.

2. A chart having a plurality of columns of transposable numbers arranged in a square, and comparable with columns of figures to be added, said chart having the differences between the transposable numbers arranged at the top of each column.

3. A chart having a plurality of columns of transposable numbers arranged in a square, and comparable with columns of figures to be added, said chart having the differences between the transposable numbers arranged at the top of each column, said differences being 9 or a multiple thereof.

4. A chart having a square outlined space divided into vertical and horizontal columns of squares, with a diagonal line ex-

tending approximately from the lower right hand corner of the square outlined space to approximately the upper left hand corner thereof; each vertical column of 5 squares being provided with a plurality of transposable numbers, with the differences between them at the top of each column, said differences being 9 or a multiple thereof, said differences being transposed and 10 ranged below the diagonal line at the bot-

tom of each vertical column, as and for the purpose specified.

In testimony whereof I have signed my name to this specification in the presence of two subscribing witnesses.

JAMES CUTHBERT PETTIT.
